UNITED STATES PATENT OFFICE.

HAROLD V. McCORMICK, OF CINCINNATI, OHIO, ASSIGNOR TO THE WARNER ELEVATOR MANUFACTURING COMPANY, OF CINCINNATI, OHIO, A CORPORATION OF OHIO.

GOVERNOR FOR ELEVATORS AND THE LIKE.

Application filed February 25, 1924. Serial No. 695,122.

To all whom it may concern:

Be it known that HAROLD V. McCORMICK, a citizen of the United States of America, and a resident of 3110 Woodburn Ave., Cincinnati, in the county of Hamilton and State of Ohio, has invented a new and useful Improvement in a Governor for Elevators and the like, of which the following is a specification.

10 An object of my invention is to provide a governor that may be used with elevator cables and the like, that is simple in construction and operation.

Another object of my invention is to provide a device for the purpose stated, that is provided with double checking means that may be successively brought into play should an elevator or the like pass from the control of the operator.

20 These and other objects are obtained by means described herein and disclosed in the accompanying drawings, in which:

Fig. 1 is a front elevation of a governor embodying my invention.

25 Fig. 2 is a sectional view on line 2—2 of Fig. 1.

Fig. 3 is a sectional view on line 3—3 of Fig. 1.

30 Fig. 4 is a side elevation of the device shown in Fig. 1, parts being broken away.

Fig. 5 is a sectional view on line 5—5 of Fig. 4.

My device comprises a base 6 that may be mounted above an elevator shaft, as shown, and comprises upwardly extending arms 7 and 8 that rotatively support a pulley 9 about which a cable 10 connected with an elevator cab or the like may extend. The pulley 9 has a circumferential groove 11 for the reception of the cable 10. The base 6 is provided with an aperture 12 through which the cable extends. A block 13 is carried by a lug 14 extending upwardly from the base 6. The block comprises a pair of spaced lugs 15 and 16 thereby providing a way 17 through which the cable 10 extends. The block carries arms 18 and 19. The arms are provided with elongated apertures 20 through which a pin 21 carried by lug 14, 45 slidably extends. A spring 22 has its opposite ends in abutment upon the lug 14 and the body or intermediate portion 23 of the block 13. The walls of the apertures 20 limit the movement of the block 13. A locking arm 34 is pivotally mounted on the base

6 and has a free end 35 disposed adjacent the block 13. The free end 35 is provided with a groove 36 for the reception of the cable 10. A finger 37 is pivotally mounted on the base 6 and is pivotally connected 60 with the arm 34 by means of a link 38. The arm 34 has formed on it a boss 39 that limits the movement of the free end of the finger 37 toward the block 13. The pivotal connections of the finger 37 and of the link 38 65 are such that when the parts are in the relation shown in Fig. 1 the weight of the arm 34 directed upon the link 38 and the finger 37 serves to retain the parts in the relation shown in Fig. 1. From the foregoing it 70 will be noted that the said pivotal connections are normally out of alignment, and that the boss 39 serves as a stop against movement of the arm about such pivotal connections or mountings. It will also be 75 noted that if the finger 37 be actuated to move the free end thereof toward the pivotal mounting of the arm 34 on the base 6 the pivots 40, 41 and 42 will be brought into alignment whereupon the pivot 41 will move 80 toward the left of the line passing between pivots 40 and 42 whereupon the arm 34 may drop about its pivotal mounting 43 on the base 6. When the arm drops, the free end 85 thereof is brought into clamping engagement upon the cable 10 against the yielding resistance of the spring 22. The arm 34 is made sufficiently long and the groove 36 is positioned in such manner that the said function is accomplished.

90 The means for actuating the finger 37 about its pivotal mounting 42 are carried by the pulley 9. The pulley is provided with two pairs of spaced brackets 44. These brackets extend away from the web 45 of the pulley on lines substantially parallel with the axis or shaft 460 about which the pulley may revolve. Each pair of brackets supports a shaft. These shafts are indicated at 46 and 47. The shaft 46 carries a weight 48 provided with a pair of arms 50 and 58, one of said arms, namely 50, being part of a bell crank lever 49. The weight is pivotally supported on the pulley by providing bearings at the free end of arm 50 and at the junction of the arms of the lever 49 and which bearings accommodate the shaft 46. A similar weight 51 provided with a pair of arms 53 and 59 of which 53 constitutes 100 part of a bell crank lever 52, is in like man-

ner supported upon the shaft 47. The free ends of the bell crank levers 49 and 52 are disposed adjacent one another and are pivotally connected by a link 54. The web 45 of the pulley is provided with apertures 56 and 57 through which the arms 50 and 58 are associated with weight 48, and arms 53 and 59 associated with weight 51 extend. The weights 48 and 51 are connected by a pair of springs 62 and 63 that yieldingly retain the arms 50, 53, 58, and 59 upon the seats 64 and 65 formed on the walls of the apertures 56 and 57 through the web 45. The weights 48 and 51 comprise radially extending flanges that normally clear the finger 37. When the pulley 9 is revolved at an excessive speed the weights are moved about their pivotal mountings on the shafts 46 and 47 and engage the finger 37 thereby causing the locking arm 34 to be dropped into binding engagement upon the cable 10. It will be readily apparent that the adjustment of the locking arm 34 and of the block 13 may be such that the cable 10 may be permitted to slide therebetween or to be securely clamped therebetween. The arm 8 carries a switch box 70 containing any suitable switch mechanism such as shown in Fig. 5. A lever 71 associated with the switch box is mounted on the stud shaft 72 and which shaft is pivotally supported by the switch box 70. As shown herein the means for mounting the switch box 70 comprises bolts 73 disposed horizontally on opposite sides of the lever 71. The shaft 72 carries an electrical contact 74 that may establish electrical communication between the electrical brushes 75 and 76. The brushes 75 and 76 are connected with a source of electrical supply controlling the normal movement of the cable 10. The lever 71 is provided with a boss 77 that may be engaged by the weights 48 and 51 for moving the lever and the shaft 72. The conductor block 74 and the brushes 75 and 76 are preferably constructed in such manner that movement of the lever 71 is yieldingly resisted. This may be accomplished in any suitable manner such as by making the brushes 75 and 76 of a yielding nature such as by giving spring qualities thereto and by providing lugs 78 on the spring arms that may lodge in pockets or recesses 79 in the conductor block 74. The weights 48 and 51 are so disposed that the normal movement of the pulley will not cause engagement of the weights upon the boss 77. The relation of these parts is such that when the movement of the pulley exceeds a predetermined rate, the lever 71 will be actuated for breaking the electric circuit embracing the brushes 75 and 76 and the electrical conductors 80 and 81, thereby stopping the motor that controls normal movement of the cable 10. Should stopping of the motor be ineffective for checking the move-

ment of the cable 10 and the cab associated therewith, so that the movement of the pulley 9 would be further accelerated, the engagement of the weights upon the finger 37 will bring the arm 34 into operation as previously explained. The rotatory movement of the pulley 9 serves to move the weights outwardly against the yielding action of the springs 62 and 63. The movement of the weights would be about the shafts 46 and 47. The connection of the bell crank levers by means of link 54, serves to equalize the movement of the weights and to obviate any variation in such movement that might otherwise result from inequality of the weights 48 and 51. 70 75 80

In the operation of my device, the spring 63 serves to hold the weights in a retracted position while the pulley rotates at a normal rate of speed. The motor that would move the cable 10 is in circuit with the electric switch associated with lever 71. Should the speed of the cable and pulley exceed a normal rate, the governor weights would be moved laterally in relation to the plane of rotation of the pulley and about their pivots 46 and 47 until the side edge of one of the governor weights 48, 51 engages lever 71 thereby pushing the lever 71 before it and breaking the circuit through the switch. 85 Ordinarily, this will bring the cable and pulley to rest. However, should the breaking of the electrical circuit prove ineffective and the speed of the cable and pulley increase further, the governor weights will be moved further laterally and the one governor weight would contact and move before it, the finger 37, thereby releasing the arm 34. The arm then falls and cooperates with the block 23 in checking the movement 90 of the cable. It should be noted that the governor means rotate about a horizontal axis and that they are carried directly by the pulley, whereby a simple and efficient structure is attained. It should also be 95 noted that the lateral movement of the weights for tripping the safety devices move laterally of the plane of rotation of the pulley and that contact and tripping of the switch mechanism does not precipitate movement of the governor weights to a more extended position for actuating the cable-gripping arm 34, but instead there must be a further increase in speed of the pulley and cable to trip the cable-gripping arm 34. 100 105 110 115 120

What I claim is:

1. In a device of the class described the combination of a pulley, a cable engaging the pulley and adapted to move therewith, an electrical switch for controlling normal movement of the cable about the pulley, a lever associated with the switch and controlling the flow of electrical energy through the switch, normally inoperative means for frictional engagement upon the cable and 125 130

means carried by the pulley for successive contacting of the lever for operating the switch and the normally inoperative means for frictional engagement upon the cable.

- 5 2. In a device of the class described the combination of a base, a pulley revolvably supported by the base, the pulley having a central perforated web, a pair of bell crank levers pivotally supported by the pulley on 70 a common side of the pulley and each having an arm extending through the perforations provided in the web, the bell crank levers being pivotally connected on that side of the pulley on which the levers have their pivot 75 mountings on the pulley, weights disposed at the ends of the levers extending through the perforations, means yieldingly connecting the weights, an electrical switch, a lever associated with the switch 10 and controlling the flow of electrical energy through the switch, a cable extending about the pulley and the normal movement of which is controlled by the flow of electrical energy through the switch, the lever and 15 the weights being disposed in such relation that they may be brought into engagement for actuating the switch, means for frictionally engaging the cable and comprising a block, a pivotally mounted arm for co-operating with the block for frictionally restraining movement of the cable, the arm being normally inoperative for effecting frictional restraint upon the cable and a finger controlling movement of the arm to 20 an operative position for frictional restraint upon the cable, the finger being adapted to be engaged by the weights upon movement of the weights about the pivotal 25 mountings of the bell crank levers 30 for rendering the finger inoperative upon the arm.

3. In a device of the class described the combination of a base, a pulley revolvably supported by the base, a cable engaging the pulley for movement therewith, the pulley having a perforated central web, seats associated with the pulley, bell crank levers each having an arm extending through the web of the pulley and normally engaging 45 the seats, the arms of the bell crank levers extending through the web having their opposite ends weighted and pivotally mounted upon the pulley, the weighted ends of the levers being on a common side of the pulley, a link pivotally connecting the bell 50 crank levers on the side of the pulley opposite to the weights, means yieldingly resisting movement of the levers from engagement upon the seats, an electrical switch for providing a closed circuit when the pulley and cable move at a normal rate, a lever controlling the switch adapted to be engaged by the weighted ends of the bell 55 crank levers upon separation of the bell crank levers from their seats, and means 60 65

for frictionally restraining movement of the cable and comprising a block, a normally inoperative arm for co-operation with the block for frictionally restraining movement of the cable and a finger normally retaining the arm in an inoperative position and adapted for engagement with the weighted ends of the levers whereby to render the finger inoperative upon the arm and to render the arm operative on the cable. 70 75

4. In a device of the class described the combination of a base, a pulley revolvably supported by the base, a cable for engagement and movement with the pulley, a pair of parallel spaced shafts carried by the pulley and disposed on a common side of the pulley, the shafts extending at right angles to the axis of the pulley, an arm and a bell crank lever pivotally mounted on each shaft, each bell crank lever having an arm extending through the pulley to the side of the pulley opposite from that side on which the shafts are disposed, each lever of one shaft having a pivotal connection with a lever on the other shaft, weights carried by the arm and lever, mounted on a given shaft, the weights being disposed on the side of the pulley opposite to the side on which are disposed the shafts, yielding means connecting the weights, an electrical switch through which electrical energy normally flows for the normal movement of the pulley and cable, a lever controlling the switch and extending into the path assumed by the weights when the pulley and cable move at an abnormal rate for breaking the flow of electrical energy through the switch, normally inoperative means for frictionally restraining movement of the cable, and means in the path of movement of the weights about their mountings on the parallel shafts for controlling movement of the normally inoperative frictionally restraining means to an operative position after the weights pass beyond the lever controlling the switch. 90 95 100 105 110

5. In a device of the class described, the combination of a pulley rotatable about a horizontal axis, a governor weight pivotally mounted on the pulley and movable about an axis parallel with the plane in which the pulley rotates and at right angles to the axis of rotation of the pulley, whereby the weight may move laterally of the pulley, means yieldingly resisting lateral movement of the governor weight, means for imparting rotary motion to the pulley and governed thereby, and a pair of trip devices for controlling the said means disposed in adjacent parallel planes for successive engagement of the governor weight as the governor weight is moved about its pivotal mounting. 115 120 125

6. In a device of the class described, the combination of a pulley rotatable about a horizontal axis, a cable movable about and 130

with the pulley, an electric switch for controlling normal movement of the cable about the pulley, a cable-gripping device normally inoperative on a cable moving about the pulley and governor weights carried by the pulley for opening the switch upon movement of the cable and pulley in excess of normal speed and for rendering the cable-gripping device operative on the cable upon a further increase of movement of the pulley and cable.

7. In a device of the class described, the combination of a pulley rotatable about a horizontal axis, a cable movable about and with the pulley, an electric switch for con-

trolling normal movement of the cable about the pulley, a cable-gripping device normally inoperative on a cable moving about the pulley and governor weights carried by the pulley and movable laterally of the plane of rotation of the pulley for opening the switch upon movement of the cable and pulley in excess of normal speed and for rendering the cable-gripping device operative on the cable upon a further increase of movement of the pulley and cable.

In testimony whereof, I have hereunto subscribed my name this 8th day of February, 1924.

HAROLD V. McCORMICK.
